UNITED STATES PATENT OFFICE

WILFRED ROTHERY WOOD, OF LONDON, ENGLAND, ASSIGNOR TO INTERNATIONAL COMBUSTION ENGINEERING CORPORATION, OF NEW YORK, N. Y., A CORPORATION OF DELAWARE

STEAM GENERATOR

Application filed January 22, 1925, Serial No. 3,921, and in Great Britain April 9, 1924.

It has been recognized that steam generators make better use of the heat of combustion of the fuel when the surfaces which transmit the heat to the water receive that heat by radiation rather than by convection, and the introduction of water tubes into the furnace chamber in a position in which they are exposed to the radiant heat therein has been proposed, partly with this object and partly to protect the walls of the furnace from damage. As a further step in the direction of utilizing radiant heat the vertical walls of the furnace chamber have been constituted by water tubes or their equivalent placed so closely together that they enclose effectively the combustion space, or at all events relieve any enclosing wall which there may be of the functions of a furnace wall. In this case provision of suitable water and steam drums is all that is necessary to complete the generator and a construction is obtained of much smaller dimensions than is possible when the main water tubes are in an uptake superimposed upon the combustion chamber. This construction may be called a furnace-shaped boiler.

It suffers, however, from a serious disadvantage, namely that the cooling effect of the surfaces to which the heat is radiated is so great that the flame of burning fuel is apt to be extinguished, so that continuous combustion is difficult. Pre-heating the air for combustion overcomes this difficulty to some extent, but the methods commonly used for burning gaseous, liquid or pulverized fuel in which a sheet of flame is produced, intended to extend throughout the chamber, are apt to fail even with preheated air. Furthermore, the temperature attained with preheated air is such that the combustion gases leave the combustion chamber at a very high temperature—an objection whatever the kind of fuel used but particularly so when pulverized fuel is burnt in suspension. For in that case a large proportion of the ash leaves the chamber together with the combustion gases at a temperature near its melting point in which condition it adheres readily to the walls of any chamber through

which the gases may pass or any superheater placed in the path of the gases.

One object of my invention is to burn fuel in the furnace-shaped boiler in such a manner as to produce maximum radiant energy 55 within the combustion chamber and to ensure continuous combustion.

Another object of my invention is to increase the surface available in a furnace-shaped boiler for absorption of radiant heat, 60 and another object is to reduce the temperature of the ashes as they leave the chamber.

Another object of my invention is a construction in which the water circulation shall be sufficiently rapid to prevent the tubes 65 from becoming overheated by the gases which impinge upon them in a state of violent combustion at a high temperature.

According to my invention a furnace-shaped boiler is fired in such a manner that 70 turbulent intermixture of the fuel and air occurs at a place as nearly as possible on the axial line of the chamber so as to localize the combustion at this place and ensure its continuance.

This object is achieved by any method of localizing combustion but preferably that in which the fuel and air are introduced into the combustion space at two or more places in streams of such velocity and direction that 80 they impinge upon each other and rapidly intermix. Preferably the direction is from the sides of the furnace and such that each stream is directed more or less tangentially to a circle. There is thus produced more or less vortex movement of the air and fuel ensuring rapid intermixture and combustion.

As is known, for development of the high temperature necessary for maximum radiation, pre-heating of the air for combustion 90 is essential; for this purpose I prefer to use a recuperator in the uptake of the boiler. This has the advantage that the combustion gases do not come into contact with the outside of the boiler so that they retain a larger quantity of heat for the purpose in question than is the case when they are allowed to return over the tubes. Furthermore, it is easier in this manner to realize an advantage of my 95 100

invention that the furnace-shaped boiler is externally readily accessible from all sides.

According to my invention the furnace-shaped boiler has not only its side walls formed of water passages but also its ends, whereby further surfaces for absorption of radiant heat are provided. To permit of escape of combustion gases there must be at one or more places a sufficient space between the water tubes or the like for this escape. In the path of these escaping gases there may be placed additional water tubes sufficient to lower the temperature of the escaping gases to that at which any ashes which they may carry are so far cooled on approaching the tubes bounding the outlet space or the aforesaid additional water tubes that they have but little tendency to adhere to superheater tubes or chamber walls.

This part of my invention therefore may be said to consist in providing water tube ends to the more or less box-shaped boiler. Conveniently, the escape of combustion gases is at one of these ends. If, in a vertical boiler the upper end is selected, there will be at this part a sufficient setting apart of the water tubes, or such a gap in the water tubes, as may be necessary for passage of the gases and beyond this additional water-tubes of the boiler, to have the cooling effect already mentioned.

One of the difficulties in connection with firing by pulverized fuel is due to the tendency for the ash to be carried away by the products of combustion, this ash subsequently depositing in the neighbourhood of the chimney stack. By one feature of my invention the gases leaving the furnace pass through a chamber containing means for causing deposition of ash carried by the gases.

When pulverized fuel is being burnt there is preferably provision at the bottom of the chamber for escape of ashes which may fall, so that here also there is a spacing apart of the tubes and if necessary additional water tubes for preventing in known manner fusion of the ashes in the ash-pit, which may be the chamber referred to in the preceding paragraph.

Since there is this necessity for an ash escape at the bottom I generally prefer to make the upper end of the chamber substantially gas-tight with water tubes and arrange the take-off for the gases at the bottom.

Other features of my invention will appear from the description of the accompanying drawings, in which:—

Fig. 1 is a vertical section through a furnace-shaped boiler constructed in accordance with my invention.

Fig. 2 is a like section on line 2—2 of Fig. 1.

Fig. 3 is a horizontal section on line 3—3 of Fig. 1.

Fig. 4 is a like section on line 4—4 of Fig. 5.

Fig. 5 is a vertical section of a modification of the boiler shown in Fig. 1.

Fig. 6 is a vertical section on line 6—6 of Fig. 5.

Fig. 7 is a fragmentary section illustrating another modification.

Fig. 8 is a fragmentary section illustrating a modification of the mode of supplying fuel to the furnace.

Figs. 9 and 10 are views illustrating the flame produced by the arrangement shown in Figs. 5 and 6.

Referring to Figs. 1, 2 and 3, the combustion space A is bounded on its four vertical sides by four sets of vertical tubes 7, 8, 9 and 10.

The upper end of the combustion space is bounded by the tubes 11 and the bottom of the combustion space is bounded by the tubes 13.

Tubes 7 enter at their upper ends the drum 14 and at their lower ends the drum 15. Tubes 9 enter at the upper ends the drum 16 and at their lower ends the drum 17. Tubes 13 are inclined to the horizontal and at their upper ends enter drum 17 and at their lower ends drum 15. Tubes 11 are similarly inclined to the horizontal and at their upper ends enter drum 16 and at their lower ends drum 14.

Tubes 8 are connected at their lower ends with a header 19 extending from drum 15 and at their upper ends with a header 20 extending from drum 16. Tubes 10 are similarly connected with a header 21 at the bottom and with a header 22 at the top, these headers extending respectively from drums 15 and 16. It will be seen that this arrangement of tubes 8 and 10 with their respective headers affords a connection between the diagonally opposite drums 15, 16, such that there is only one general direction of passage of fluid from the lower to the upper drum and the length of this passage is the same whichever tube conducts the fluid.

As indicated in Fig. 4, each of the tubes of sets 7, 8, 9 and 10 have on opposite sides fins 23, so that when the tubes are assembled the fins overlap, thus making a substantially gas-tight chamber which, however, is made completely closed on its four sides and top by means of insulating material 24 and a shell 25, both of which may be of very light construction, since they have not to withstand a temperature appreciably higher than that of the water in the tubes. If preferred, the fins may closely abut against each other. In any case they prevent the building up of ashes between the tubes which is liable to occur if any sort of brickwork be exposed between the tubes.

The chamber thus formed is open at the bottom and communicates with an ash-pit 26 situated by an ash tunnel 27. This ash pit may contain baffles, not shown in the drawings, suitable for causing the gases to

- change their direction of travel and thus to deposit ashes suspended in them.
- The drum 16 is connected at each end with the corresponding end of drum 15 by a number of tubes 28 which are outside the combustion chamber and constitute the down-comer tubes of the circulatory system. They are of such size and number that they do not hamper the extremely rapid circulation in the boiler.
- The tubes 13 are upcomer tubes from drum 15 to drum 17. Tubes 7 and 9 are upcomer tubes from drums 15 and 17 respectively to drums 14 and 16 respectively, and tubes 8 and 10 are upcomer tubes from header 19 to header 20 and from header 21 to header 22 respectively.
- Drum 16 is a combined steam and water drum.
- 20 The circulation is from drum 16 to drum 15 and thence upwardly through all the tubes 7, 8, 9, 10, 13 and 11 back to drum 16.
- 25 Drum 16 is suspended from the structural steel-work 30 and this suspension, coupled with the fact that the tubes 7, 9 and 13 are bent and that the tubes 8 and 10 are connected with headers, permits the boiler to expand and contract without placing any undue stress on the parts.
- 30 For the purpose of introducing the fuel there is provided at each of the four upright corners of the combustion space and at a level some distance below that of the drum 14, a burner 31 constructed to deliver 35 a thin sheet of fuel, sandwiched between sheets of air, into the chamber in a substantially vertical plane.
- For the purpose of admitting these burners suitable spaces are left between the tubes at the corners. The direction in which the fuel and air proceed in these burners is that indicated in Fig. 3. That is, the directions are substantially tangential to the circle indicated at the centre of the chamber; the result of this is that when the fuel streams meet a vortex is set up, the axis of which is parallel to the line of draught. The fuel is introduced at high velocity, preferably with a blast of carrying air by a usual 50 form of controlled feeder mechanism, such as is indicated in Fig. 5.
- The main portion of air necessary for combustion is supplied at high temperature around the fuel streams either by induction 55 or under pressure, preferably the former. The air thus supplied is not cooled by passing over water tubes before it enters the furnace.
- In consequence of this mode of introducing the fuel, the combustion is promptly instituted and is completed in a very short time, the flame being short, concentrated and intensely hot. The proportion of air admitted for combustion is preferably close to the theoretical.
- The combustion gases leave the chamber by passing among the nest of tubes 13 which are at such a temperature that they cool the gases sufficiently to prevent fusion of the ash collecting in the ash-pit but not to a much lower temperature, so that the gases can superheat the steam which flows by way of pipe 38 from drum 16 through the superheater 37 placed in the uptake 32, the gases passing over this superheater. After 70 leaving the superheater the gases, still at a high temperature, pass through the recuperator 35' consisting of a box subdivided by thin metallic partitions into compartments 33 and 34. The hot gases pass by the compartments 33 while air is drawn through compartments 34 into the passage 35 which has branches 36 leading to the burners. Dampers 36^a control the air supply and a damper, not shown, is provided in the off-take above the recuperator.
- 75 It is to be noted in Fig. 2 that the rows of tubes 13 have different tube spacings, the tubes of the first and second rows being widely spaced whereas those of the lower rows are more closely spaced, a staggered relationship being always observed. This arrangement restricts the passage for combustion gases in accordance with the shrinkage of the latter in volume due to the absorption 80 of their sensible heat.
- 85 In the construction shown in Figs. 4, 5 and 6 the draught is upwards instead of downwards. The general construction is the same as that already described but the offtake is 90 above the combustion space, necessitating the proper spacing apart of tubes 11. The recuperator 35' is divided, the parts being spaced to leave the flue channel 39 controlled by valve 40. Tubes 13 above the ash-pit 26 may be reduced in number in this form since 95 their function is only to cool such portion of the ash as falls between them.
- 100 To suit the direction of draught the fuel is admitted at each of two opposite sides in thin spaced sheets in a downwardly inclined direction by the sets of burners 41, producing flames which impinge as indicated in Fig. 10.
- 105 The mode of firing illustrated in Fig. 8 is substantially the same but the sheets of fuel are delivered substantially horizontally and at a lower level in the chamber.
- 110 In the construction shown in Fig. 7 there is a fifth drum 18 which serves as the steam drum. It is connected with drum 16 by tubes 12 and with drum 14 by the short tubes shown.
- 115 The constructions illustrated have the advantage that any side wall may expand with relation to any other side wall with perfect freedom and the top and bottom of the boiler 125 may also expand without causing strains.
- 120 The term water-tube means any tube which affords passage for fluid, and includes passages in what are commonly called boiler sections.

While a single row of water tubes for each vertical wall of the furnace chamber is generally sufficient, two or more rows of tubes, preferably staggered, may be used.

5 No specific claim is made herein to the up-draft arrangement, the same being subject matter of my copending application Serial No. 51,533, filed August 21, 1925; nor to the specific type of combustion illustrated in 10 Figures 9 and 10, the same being the subject matter of my copending application Serial No. 51,534, filed August 21, 1925.

Having thus described the nature of the said invention and the best means I know 15 of carrying the same into practical effect, I claim:—

1. A furnace-shaped boiler having six walls, one of which receives its circulating water from inclined water passages defining 20 the bottom of the combustion chamber while the opposite wall receives its water from a drum or header at the lowest point of the boiler and discharges it through inclined tubes defining the top of the chamber.

2. A furnace-shaped boiler having an upper and a lower drum or header placed diagonally opposite to each other with respect to the combustion chamber and connected together by upright tubes constituting at least 25 one wall of the chamber at right angles to the axes of the drums, in such a manner that fluid traveling from drum to drum through any tube of this wall passes through the same distance.

3. A furnace-shaped boiler having the circulation referred to in claim 2 wherein downcomers connect the diagonally opposite drums.

4. A stationary power boiler defining its 40 own combustion space from an end of which the gases of combustion leave and comprised of rows of tubes with appropriate drum and header means, the tubes of the boiler being so disposed that circulation is very rapid, means 45 near the other end for introducing a fuel to be burned in space in said combustion space in a manner that the boiler is subjected to heat of convection as well as of radiation and that violent combustion occurs, a metallic 50 air preheater, means for subjecting the heater to waste gases of combustion, means for introducing the air to the combustion space, and heat absorbing means in advance of the heater and associated with the boiler for 55 lowering the temperature of the gases leaving the combustion space to a point where rapid destruction of the air preheater does not occur.

5. A stationary power boiler defining its 60 own combustion space from one end of which the waste gases of combustion leave, and largely comprised of rows of upright radiant heat tubes with appropriate drum and header means connected to secure rapid circulation, 65 the amount of evaporating surface of the

tubes defining the combustion space being such that the gases leave such space at very high temperature, convection tubes over which the gases leaving the space pass having an amount of evaporating surface such 70 that the gases leave the same at high temperature, a waste gas combustion air preheater beyond such convection tubes adapted to lower the temperature of the gases so that their final exit temperature is within allowable limits, and means for introducing such preheated air and fuel to be burned in space under conditions to produce violent combustion with high furnace temperature head.

75 In testimony whereof I have signed my name to this specification.

WILFRED ROTHERY WOOD.
